UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

AUTOMOBILE-HORN.

1,110,989.

Specification of Letters Patent. Patented Sept. 15, 1914.

Continuation of application Serial No. 695,386, filed May 6, 1912. This application filed September 27, 1913. Serial No. 793,080.

To all whom it may concern:

Be it known that I, RAY H. MANSON, a citizen of the United States, residing at Elyria, in the county of Lorain and State of Ohio, have invented certain new and useful Improvements in Automobile-Horns; and I do hereby declare the following to be a full, clear, and exact description of the invention, such as will enable others skilled in the art 10 to which it appertains to make and use the same.

This invention relates to automobile horns, and more particularly to electric horns in which the sound producing device is controlled by an electric current, the particular 15 object of my invention being to improve the horns now being manufactured and placed upon the market.

Another object of my invention is to produce a short horn, such as is especially adapted 20 for use upon motor cycles. To accomplish this, I have arranged the apparatus in the rear part of the horn in a compact structure, making it as flat as possible so as to 25 shorten the horn.

Other particular objects of my invention will be better understood from the particular 30 description which is to follow. In this description I have described one embodiment of my invention, which is illustrated in the accompanying drawing.

This application is a successor of my application #695,386, filed May 6, 1912, which application but not the invention disclosed 35 therein is abandoned, in view of the present application.

Figure 1 is a section through an automobile horn illustrating my invention, part of the resonator being shown in elevation. Fig. 40 2 is a rear end elevation of the parts shown in Fig. 1 with the rear cover removed. Figs. 3 and 4 are details.

Referring now to the drawing and to the embodiment of my invention illustrated 45 therein, at 7 I have shown a main frame piece or supporting member, the main portion of which is flat, but the top portion of which is dished by stamping or other means, as shown at 6, the side 5 being shown inclined. The bottom 8 of the dished portion 50 contains an opening 9 which in the form shown is eccentric with respect to the bottom of the dished portion. A sonorous member,

preferably a vibratile diaphragm is mounted upon the edge of the dished portion in any 55 suitable way, the diaphragm being preferably concentric with the dished portion. In the form shown, the diaphragm is clamped between the front 11 of the frame and the frame piece 7, the three parts being connected 60 together by some suitable means, such as screws 12. An opening 13 is formed in the front 11 for the passage of sound waves, and a resonator 14 may be mounted in this opening. The lower part 15 of the main frame 65 piece 7 constitutes a bracket for connecting the horn to any suitable support. Of course, this bracket may be separate from the frame piece. I prefer to mount an anvil 16 upon the diaphragm in order that the vibrating 70 member may strike thereagainst to cause the diaphragm to sound a signal. This serves to protect the diaphragm and to concentrate the blow upon the geometrical center thereof. Electromagnetic means including an 75 armature 17 are employed. In the form shown I have illustrated an angle armature. As shown, the armature constitutes what is practically a right angle and may be cut from an ordinary piece of angle iron, thus 80 greatly reducing the cost of manufacture and improving the efficiency of the device. This armature is connected to the frame, and in the form shown, I employ a resilient member, such as a flat spring 18, connected by 85 some suitable means, such as a screw 19 to the armature. This may be connected to the limb 20 of the armature, which is preferably substantially parallel to the diaphragm. The spring is connected to the limb 20 adjacent 90 the bent part of the armature, and at the other end the spring is connected to the main frame piece 7 by some suitable means, such as screws 21. In the form shown, this connection is at the edge of the opening 9 in 95 the bottom of the dished portion of the main frame piece 7.

The limb 20 of the armature carries the contact 22, preferably upon the back side thereof. The other limb 23 of the armature 100 is adapted to be acted upon by electromagnetic means, such as electromagnets 24. These magnets consist of coils 25 which are mounted upon a core composed of a plurality of punchings 26. In the form shown, 105 these punchings are U-shaped and have a

winding upon each limb thereof. The punchings are connected preferably to the bottom portion or back side of the frame through suitable means, such as a support 30 and screws 31, the support 30 serving to space the core from the frame. In the form shown, I have illustrated the magnets as being connected to the edge of the opening 9, opposite the connection of the armature of such frame piece. At 40 I show a flexible member, here illustrated as a spring which is connected at each end to the frame. I prefer to connect this to the main frame piece 7 upon the edge of the opening 9, being best mounted upon the bottom of the dished portion 5. Any suitable connecting means, such as screws 42 and supports or spacing members 43 are employed. This member carries a contact 45 as shown intermediate its ends, and in a position to co-operate with the contact upon the armature to open and close an electric switch when the armature is vibrated.

In Fig. 3 I have shown means for locking the spring 40 in position to prevent its being shifted by the vibration of the armature, and the changing of the tone of the horn thereby. This locking means consists of a second screw 60 connected by an intermediate member 70 to one of the screws 42. One end 71 of the member 70 is folded over and enters a perforation 72 in the frame 7. This locks the screws together in a well known way, preventing the screws 42 from shifting their position.

It will be obvious to those skilled in the art that numerous and extensive departures from the form and the details of the apparatus here shown may be made without departing from the spirit of the invention, the same being herein shown solely for the purpose of illustrating one specific embodiment of the invention.

I claim:

1. In an automobile horn, the combination of a frame, a sonorous member in said frame, an angle armature for causing said member to sound a signal, one limb of said armature adapted to operate upon said member, a contact on such limb, electromagnetic means for acting upon the other limb of said armature, a flexible member connected at each end to said frame, and a contact upon said flexible member adapted to co-operate with the contact upon the armature.

2. In an automobile horn, the combination of a frame, a sonorous member, an angle armature, one limb of which is adapted to operate said member to cause the same to sound a signal, a contact on such limb, a spring for connecting said armature to said frame, electromagnetic means adapted to operate upon the other limb of said armature to actuate the same, a spring con-

nected at each end to said frame, and a contact carried by said spring adapted to co-operate with the contact upon the armature.

3. In an automobile horn, the combination of a frame, a sonorous member, an anvil on said sonorous member, an angle armature, one limb of which is adapted to strike said anvil when the armature is vibrated, a contact on said limb, a spring for connecting said armature to said frame, electromagnetic means for operating upon the other limb of the armature to actuate such armature, a flexible spring connected at each end to said frame, and a contact carried by said spring intermediate its ends adapted to co-operate with the contact upon the armature.

4. In an automobile horn, the combination of a frame plate dished at its upper part, an opening in the bottom of the dished part, a sonorous diaphragm mounted over the top of the dished part, an armature adapted to operate upon said diaphragm connected to the edge of the opening in the bottom of the dished part, and a magnet adapted to operate upon the armature connected to the bottom of the dished part adjacent the edge of the opening therein.

5. In an automobile horn, the combination of a main frame member, dished at the top thereof, a sonorous diaphragm mounted over the top of the dished portion, said dished portion having an opening in the bottom thereof, an armature connected to the edge of the opening, a spring for connecting the armature to the edge of the opening, a magnet for operating said armature, means for connecting said magnet upon the bottom of the dished portion and near the edge of the opening therein, and means for spacing said magnet from such bottom.

6. In an automobile horn, the combination of a frame piece having an opening therein, a front casing, a diaphragm mounted between the casing and frame piece and exposed through the opening in the frame piece, means for operating said diaphragm including an electromagnet mounted on the back side of said frame piece and extending substantially parallel to the diaphragm, means to connect one end of said magnet to the edge of the frame piece with its armature operating end adjacent the center of the diaphragm, an armature for actuating the diaphragm associated with the armature actuating end of the magnet and means including a spring connecting the armature to the edge of the frame piece and normally positioning it out of engagement with the diaphragm and adjacent the central portion thereof.

7. In an automobile horn, the combination of a frame piece having a relatively large opening therein, a vibratile sonorous

- diaphragm associated with the frame piece and exposed from the rear through the opening in the frame piece, means for operating said diaphragm which acts upon the 5 same through the opening, said means including an electromagnet mounted upon the back side of the frame piece and having its core extending over the opening and the exposed part of the diaphragm and substantially parallel to the diaphragm, means to connect one end of the electro-magnet to the edge of the frame piece and normally holding it in position with the armature actuating end adjacent the central portion 10 of the diaphragm, an armature for actuating the diaphragm controlled by said magnet mounted over the opening in the frame piece, means including a spring connecting the armature with the frame piece and normally holding the armature out of engagement with the diaphragm and with its diaphragm actuating portion over the central portion of the diaphragm and an electric switch controlled by the armature.
- 15 8. In an automobile horn, the combination of a frame piece having an opening therein, a front casing, a diaphragm clamped between said casing and frame piece and exposed through the opening in the frame piece, means for operating said diaphragm acting through said opening including an electromagnet mounted on the frame piece and having its cores extending substantially parallel to the diaphragm over the opening 20 in the frame piece, means to connect the magnet to the frame piece, an armature fastened to the frame piece opposite the magnet, said armature extending over the opening in the frame piece and vibrating the diaphragm through said opening when the magnet is operated, a spring connecting the armature to the frame piece, means to connect the spring to the frame piece and a rear casing to inclose said actuating 25 means.
- 30 9. In an automobile horn, the combination of a frame piece having a relatively large opening therein, a front casing having its edges turned backward over the edge of the frame piece, a diaphragm between the frame piece and the casing front, said casing front having an opening therein for the egress of sound waves, a resonator in said opening, said diaphragm extending over the opening in the frame piece and exposed therethrough, an anvil on the diaphragm, means for actuating said diaphragm including a pair of electromagnets having integral polar extensions parallel to each other, means connecting the polar extensions together, said polar extensions and means being connected to the frame piece with the polar extensions extending over the opening in the frame piece and parallel to the diaphragm, means for connecting said polar 35 extensions to the frame piece passing through the polar extension connecting means and the frame piece, magnet windings mounted on said polar extensions, an armature for said magnet adapted to be actuated by the magnet to strike the anvil on the diaphragm to vibrate said diaphragm, said armature being over the opening in the frame piece, a flat spring connected to the armature at one end and at the other end to the frame piece substantially opposite the point of connection of the polar extensions to the frame piece and an electric switch including contacts controlled by said armature.
- 40 10. In an automobile or motor cycle horn, the combination of a casing front having an opening therein for the egress of sound waves, a resonator in said opening, a supporting member having a large opening therein, a diaphragm clamped at its edges between the casing front and the supporting member, means to connect said diaphragm, said casing front and said supporting member together, said diaphragm being exposed to the rear through the opening in the supporting member, a pair of electromagnet coils, a core for said coils built up of a plurality of U-shaped punchings extending substantially parallel to the diaphragm, means for connecting said U-shaped punchings to the supporting member, the magnet coils being mounted upon the core, an armature for said magnets adapted when vibrated by the magnets to cause the diaphragm to vibrate to sound a signal, a flat leaf spring connected to the armature and to the supporting member substantially opposite the point at which the magnet core is connected to the supporting member, and an electric switch including two contacts, one of which is supported from the supporting member and the other of which is controlled by the armature.
- 45 11. In an automobile or motor cycle horn, the combination of a casing front, a supporting member, a diaphragm clamped at its edges between the casing front and supporting member, an armature connected to the supporting member by a spring and adapted when vibrated to actuate the diaphragm to cause it to sound a signal, electro-magnetic means for operating the diaphragm including a pair of polar extensions extending substantially parallel to the diaphragm and built up from a plurality of U-shaped punchings connected at the base to the back side of the supporting member, magnet coils mounted on said polar extensions extending substantially parallel to the diaphragm, means to space the punchings from the supporting member, a circuit for said magnets and a switch controlling said circuit, including two contacts one of which

is supported from the supporting member and the other of which is controlled by the armature.

12. In an automobile or motor cycle horn, the combination of a casing front having a circular opening in the central portion thereof for the egress of sound waves, a resonator in said opening for the amplification of sound waves, a supporting member having a large opening therein, a vibratile sonorous diaphragm clamped between the front and the supporting member, a plurality of screws for clamping the diaphragm, the front and the supporting member together, the portion of the casing front in front of the diaphragm being struck outward away from the diaphragm to provide room for the diaphragm to vibrate, an armature for actuating the diaphragm and causing it to vibrate to sound a signal, a flat leaf spring connected to the armature and to the supporting member and adapted to return the armature, when displaced, to normal position where it disengages the diaphragm, electromagnetic means for operating the armature including a pair of parallel polar extensions built up of a plurality of U-shaped punchings connected to the supporting member opposite the armature connection, the core pieces when thus mounted on the supporting member extending substantially parallel to the diaphragm, electromagnet coils on the polar extensions, means to space the U-shaped punchings from the supporting member, means to attach the punchings to the supporting member, and a switch controlling said electromagnetic means including a contact supported from the supporting member and a second contact controlled by the armature and operated when the armature is actuated by the magnets.

13. In an automobile or motor cycle horn, the combination of a vibratile sonorous diaphragm, flat supporting means therefor, an opening in said supporting means through which the rear of the diaphragm is exposed, a vibratile armature disengaging said diaphragm when in normal position, a spring connecting said armature to the supporting means, adapted to return said armature to normal position when the armature is displaced therefrom, electromagnetic means for displacing the armature and causing it to actuate the diaphragm to vibrate the same to sound a signal, said electromagnetic means including a pair of parallel polar extensions built up from a plurality of U-shaped punchings, magnet coils mounted on the polar extensions, the polar extensions and magnet coils being substantially parallel to the diaphragm, means to connect the electromagnetic means to the supporting member and a switch controlling said electromagnetic means including two contacts, one of which

is supported from the supporting member and the other of which is controlled by the armature.

14. In an automobile or motor cycle horn, the combination of a flat supporting member having an opening therein, a front casing, a diaphragm clamped between said casing and supporting member and extending over the opening in the supporting member, means for operating said diaphragm including an electromagnet mounted on the edge of said supporting member and having its magnets mounted with the core thereof substantially parallel to the diaphragm, an armature for actuating the diaphragm to vibrate the same normally disconnected from the diaphragm, a spring for returning the armature to normal position when displaced therefrom by the magnet, said spring connecting the armature to the supporting member.

15. In an automobile or motor cycle horn, the combination of a supporting member having a relatively large opening therein, a diaphragm associated with the supporting member and exposed through the opening therein, means for operating said diaphragm acting upon the same through the opening including electromagnetic means mounted upon the back side of the supporting member and having its core extending over the opening and the exposed part of the diaphragm and substantially parallel to the diaphragm, an armature for actuating the diaphragm operated by said magnet normally disconnected from the diaphragm, said magnet mounted over the opening in the supporting member, and a spring connecting the armature with the supporting member, said spring returning the armature to normal when displaced therefrom by the magnet and a switch operated by said armature controlling the magnet.

16. In an automobile or motor cycle horn, the combination of a supporting member having an opening therein, a diaphragm associated with the supporting member and exposed through the opening therein, means for operating said diaphragm including an electromagnet mounted upon the back side of said supporting member and extending substantially parallel to the diaphragm with its free or armature actuating end toward the center of the diaphragm, an armature for actuating the diaphragm operated by said magnet and an electric switch governing the flow of current through the magnet controlled by the armature.

17. In an automobile or motor cycle horn, the combination of a supporting member having an opening therein, a diaphragm associated therewith, electromagnetic means mounted on the back side of said member with its core and winding substantially parallel to the diaphragm and with its free

end toward the center of the diaphragm, the armature of said electromagnetic means being fastened to the supporting member opposite the magnet and an electric switch controlled by the magnet.

18. In an automobile or motor cycle horn, the combination of a supporting member having an opening therein, a diaphragm associated with said opening, electromagnetic means including a core, an armature, and coils mounted on said core, said electromagnetic means being mounted on the back side of said supporting member with the core of the magnet substantially parallel to the diaphragm and the free or armature actuating end of the magnet extending toward the center of the diaphragm, said armature actuating the diaphragm when operated by the magnet.

19. In an automobile or motor cycle horn, the combination of a flat frame piece having a large opening therein, a diaphragm mounted in front of the frame piece and exposed through said opening, an electromagnetic net, means to mount the magnet on the back side of the frame piece including a core formed of a plurality of punchings fastened at one end to the back side of the frame piece and extending substantially parallel to the diaphragm, an armature controlled by said magnet for actuating the diaphragm normally disengaged from said diaphragm, said armature mounted on the back side of the frame piece, means for mounting the electromagnet and armature on the frame piece and an electric switch having contacts controlled by the armature.

20. In an automobile or motor cycle horn, the combination of a substantially flat supporting member having an opening therein, a front casing, a diaphragm clamped between said casing and supporting member and extending over the opening in the sup-

porting member, means for operating said diaphragm including an electromagnet mounted on the back side of said supporting member, means for connecting one end of said magnet to the supporting member and holding said magnet in position with the core substantially parallel to the diaphragm and the free or armature actuating end of the magnet extending toward the central portion of the diaphragm, an armature for actuating the diaphragm and means including a spring for connecting the armature to the frame piece, said spring adapted to return the armature to normal position when displaced therefrom by the magnet, and an electric switch controlled by the magnet.

21. In an automobile horn, the combination of a supporting member having an opening therein, a diaphragm associated therewith, electromagnetic means for actuating said diaphragm, said means comprising an armature a magnet core and a winding thereon, said core and winding being mounted upon the supporting member with the core and winding substantially parallel to the diaphragm and extending with the free or armature actuating end of the magnet toward the center of the diaphragm, said armature being normally adjacent the center of the diaphragm and normally disengaging the same, means including a spring for connecting the armature to the supporting member, and means for connecting one end of the magnet core to the back side of the supporting member.

In testimony whereof, I have affixed my signature in the presence of two witnesses, this 26 day of Sept., 1913.

RAY H. MANSON.
